MOISTURE CONTROLLER

Hervey G. Cram, Appleton, Wis., assignor to P. D. Cram, Appleton, Wis.

Application August 15, 1938, Serial No. 225,029

5 Claims. (Cl. 34—48)

This invention appertains broadly to means for controlling the volume of steam delivered to any device according to the amount of water of condensate formed, and more specifically to the dryers of a paper or like machine.

One of the major requirements in the art of paper-making is the necessity of maintaining a uniform predetermined moisture content in the sheet as delivered from the paper machine.

It is an established fact that the quality of the finished sheet is enhanced if the moisture content is of the correct amount, and this ratio of moisture to solids is constant. The percentage of moisture in the sheet affects the strength, surface, flexibility, etc. It also affects the operation of the paper machine, as a sheet over-dried has a tendency to snap off in the dryers or at the calender stack, resulting in a considerable loss of machine time; or, if the sheet contains too much moisture, it may be blackened in passing the rolls of the calender stack. Uneven moisture content along the run of the sheet affects the general quality so that these variables are carried through to the printing processes, which result in printing imperfections. Further, anything less than the proper specified moisture content in the sheet will result in a considerable monetary loss to the paper manufacturer, in that the difference in the percentage of moisture content in the sheet and a greater specified moisture content, based on the cost of the finished sheet, is a direct loss.

It is, therefore, one of the primary objects of my present invention to provide a means to regulate the flow of steam to the dryers of a paper machine, so as to maintain automatically the specified percentage of moisture content in the sheet as it is being made on the paper machine.

Another salient object of my invention is to provide means for determining the moisture content in the sheet by the rate of condensation in one or more of the dryend dryers of the drying section of a paper machine.

A further important object of my invention is to provide means for automatically regulating the flow of steam to the drying rollers of a paper-making machine according to the rate of condensation in a specified drying roll.

A still further object of my invention is to provide a simple and durable means for actuating a steam valve in accordance with the amount of water of condensation being taken from a drying roll.

With these and other objects in view, the invention consists in the novel construction, arrangement, and formation of parts, as will be

hereinafter more specifically described, claimed, and illustrated in the accompanying drawings, in which drawings:

Figure 1 is a diagrammatic view of a part of the drying section of a paper-making machine, showing my novel device incorporated therewith.

Figure 2 is an enlarged, fragmentary, transverse sectional view through a drying roller at the dry-end of a paper-making machine, showing my improved device incorporated therewith, the various parts of the device being shown in more or less diagrammatic form and laid out to the best advantage to facilitate the understanding of the operation of the present invention.

Referring to the drawings in detail, wherein similar reference characters designate corresponding parts throughout the several views, the letter S generally indicates the drying section of a paper-making machine. As shown, the drying section includes rolls 1, 2, 3, 4, and 5 at the front or wet end thereof; and rolls 6, 7, 8, 9, 10, and 11 at the rear or dry end thereof. There can be as many intermediate drying rolls as may be desired, and, as stated, Figure 1 is of a diagrammatic nature.

The paper sheet 12, shown in dot-and-dash lines in the drawing, is trained over the various rolls in the usual manner, and these rotating rolls are all connected at their axial centers through couplings 13 with branch pipes 14 leading from a common steam supplying pipe or header 15 or from any other suitable source of supply. This header 15 is connected by means of a pipe 16 and suitable couplings with a steam delivery pipe 17. The pipe 17 has incorporated in the length thereof a valve 18 for controlling the flow of steam through the pipe 17 and to the battery of drying rolls.

The water of condensation from the various rolls can be removed in a manner similar to that shown in my prior Patents Nos. 1,919,416 and 2,045,634, issued respectively on July 25, 1933, and June 30, 1936. Thus, positioned in each roll is a syphon pipe 19, which leads out of the coupling 13. In the present illustration, all of the syphon pipes 19 from the various rolls, with the exception of the roll 9, lead directly to the header 20 for the water of condensation, and this water is finally drained off or returned to the desired point of use. The roll 9 at the dry end of the cylinder is used in the present instance as a test roll, and the amount of water of condensate from said roll 9 governs the flow or volume of steam delivered to the various drying rolls.

In general practice, the steam requirement of

the initial dryers 1, 2, 3, etc. at the wet end, where the sheet is delivered in its wettest condition, will be greatest, decreasing in each successive dryer as the sheet reaches a drier state, until at the last dryers 10 and 11 the sheet has very nearly reached the required dryness, and the rate of condensation in these dryers is practically nil under normal operation.

It is obvious that with a fixed flow of steam to the supply header 15, the steam requirement of the wet-end dryers 1, 2, 3, etc. will be fairly constant, the constancy of steam requirement decreasing on successive dryers until near the dry-end dryers 7, 8, 9, 10, and 11 a marked variation in steam requirement is apparent. This variation is effected by some variation in the sheet as entering the dryers; that is, the sheet may vary in thickness (weight), or the make-up of the sheet may vary in freeness (more or less fibrous). The more fibrous or free sheet is less resistant to the evaporation of moisture, and, naturally, the thicker or heavier sheet, containing proportionately more moisture, is more difficult to dry.

With an excessive drying burden effected by one or both of these variables in the sheet, the first dryers 1, 2, 3, etc. will transfer this excessive drying burden to successive dryers in the section. This transfer of drying burden to the dry-end dryers will increase the rate of condensation in these dryers, and this increase is proportional to the amount of moisture in the sheet at that point. Therefore, by selecting a dryer (such as drying roll 9) at the dry end as a test dryer, and measuring the condensate therefrom as to rate of flow, and providing a means for transmitting this variation to the control valve 18 in the steam supply line 17, the rate of drying on the complete section of dryers will vary with the variation in the sheet, with the result that a uniformly dried sheet will be delivered from the dryers.

Referring more particularly to the drying roll 8, it will be seen that the condensate is removed continuously therefrom through the siphon pipe 19 to a vertical pipe consisting of an upper section 21, an intermediate relatively long section 22, and a lower section 23. The upper and intermediate sections are connected through the medium of a desired steam trap 24, and the intermediate and lower pipe sections are connected together through the medium of a desired steam trap 25.

The lower pipe section 23 discharges at a considerably lower pressure into a hot well, vacuum pump, atmosphere, or the like. The intermediate pipe length 22 has incorporated therein, at a point intermediate its length, a moisture control 26.

A pressure relief is provided for the pipe section 21 by means of a communicating pipe 27, with a diaphragm pressure differential control valve 28 therein. This differential control valve 28 has one side of its diaphragm equalized as to pressure with the supply pipe 14, and the other side equalized as to pressure with the condensate return pipe section 21, by means of pipes 29 and 30. The adjustment of differential in pressure across the valve is by means of the spring in the valve, which assures a constant predetermined pressure differential across the dryer.

The trap 24 is provided in the condensate return pipe section 21 to prevent passage of steam and to also prevent the dryer pressure from being transferred to the moisture controller 26. The

moisture controller 26 is in the nature of a valve, and is provided with an orifice 31, the size of which is controlled by means of an adjustable hand wheel 32, actuating a needle valve body.

5 The discharge from the moisture controller 26 is to the trap 25, which effects a constant pressure on the discharge of the moisture controller 26. A communicating pipe 33 between the intake and discharge of the moisture controller 26 equalizes 10 the differential across the moisture controller 26, except as affected by the hydrostatic head of the column of condensate held back by the moisture controller 26.

The pressure head of the column of condensate 15 above the moisture controller 26 is communicated to the diaphragm of the pilot valve 34 through pipe 35, which regulates the pressure to the diaphragm 36 of the control valve 18 in the steam supply pipe 17.

20 The upper connection of pipe 33 to the pipe section 22 is purposely high in order to avoid by-passing the condensate past the moisture controller 26 before the head of condensate has fully opened the steam control valve 18.

25 The pilot valve 34, as stated, controls or regulates the pressure to the diaphragm 36 of the steam control valve 18, and the pressure to the diaphragm 36 may be compressed air or the like. In the present instance, I have provided a pipe or tube 37 leading from a suitable source of compressed air, and this pipe leads to one side of the diaphragm 36. However, the pipe 37 has incorporated in the length thereof the pilot valve 34, which includes the valve body 38 movable toward and away from its seat according to the pressure of the column of the water of condensate in the pipe 22.

30 It is to be noted that the control valve 18 is normally held on its seat by the spring 39 thereof, bearing on the diaphragm 36, and that air pressure working on the diaphragm 36 controls the opening of the control valve 18.

35 The air supply pipe 37 can be provided with a strainer 40 and a reducing valve 41. The valve 41 reduces the pressure to a constant predetermined amount, which, in the present instance, has been set to fifteen pounds. Thus, the pressure leading toward the valve body 38 is constant. An orifice 42 is provided on the right-hand side of the pressure reducing valve 41, and this orifice is equal in area to the orifice in the pilot valve 34 when the pilot valve is in its wide-open position, that is, when the valve body 38 is entirely off its seat. When in this position, the pressure is "zero" between the orifice 41 and the diaphragm 36 of the steam control valve.

40 The injection of the valve 38 into the pilot valve reduces the discharge to the atmosphere (pipe 43) proportionately, and raises the pressure in the pipes leading to the diaphragm 36, 45 which results in the forcing of the stem of the control valve 18 downwardly. This opens the control valve 18 against the action of its spring 39, thereby passing an amount of steam proportionate to the pressure head in the column of condensate in the pipe 22.

45 From the above it can be seen that the pressure head of the column of condensate in pipe 22 is transmitted to the diaphragm of the diaphragm pilot valve 34, which forces the spindle or valve body 38 into the valve casing, thereby reducing the area of the orifice 44 of the air escape atmosphere pipe 43 proportionately.

50 The operation of the device is as follows: A 70 variation in the sheet entering the dryers, such

as an increase in the weight of the sheet, causes a part of the drying burden to be transferred to the successive dryers in the section, so that the dry-end dryers are forced to condense a greater amount of steam. This additional rate of flow of condensate will raise the head of the column of condensate in pipe 22 above the orifice of the moisture controller 26; and this pressure head will be communicated through pipe 35 to the pilot valve 34, to the control valve 18, opening the valve 18 and allowing a proportional increase of steam to be supplied to the entire dryer section, sufficient to dry the heavier sheet to the same percentage of dryness as the previous normal weight sheet.

A decrease in the weight of the sheet reduces the head of the column to condensate, and this decrease in pressure head is communicated through the pilot valve 34 to the control valve 18, effecting a proportional closing thereof. This reduces the rate of dryness on the initial dryers, thereby forcing the subsequent dryers to assume their proper share of the drying.

Obviously, my invention can take various forms, and, hence, the form shown and described is merely to be taken as illustrative of one form of my invention.

Changes in details may be made without departing from the spirit or scope of my invention, but what I claim as new is:

1. In a paper-making machine, a drying section including a plurality of drying rolls, a header pipe for steam, a pipe for supplying steam to said header, a control valve in the supply pipe, means for operating said valve by fluid pressure, a pilot valve for controlling the flow of fluid to the first-mentioned valve, means for supplying steam to the rolls from said header pipe, a header for the water of condensation, pipes for receiving water of condensation from the rolls and conducting the same to the header for the water of condensation, means for operating the pilot valve from the head of water in one of the pipes receiving water of condensation from one of the rolls, and means for governing the flow of water of condensation through said pipes.

2. In a paper-making machine, a drying section including a plurality of drying rolls, means for supplying steam to all of said rolls including a header and a steam supply pipe leading to the header, a valve in said steam supply pipe, means for removing water of condensation from one of said rolls including a vertically disposed

pipe, steam traps in said last-mentioned pipe, means for operating the valve for the steam supply pipe by fluid pressure, a pilot valve for controlling the flow of fluid pressure to said last-mentioned means, means for operating the pilot valve by the head of water in the vertical pipe between the steam traps, and means for controlling the flow of water of condensation in the vertical pipe.

3. In a paper-making machine, a drying section including a plurality of drying rolls, means for supplying steam to all of said rolls including a header and a steam supply pipe leading to the header, a valve in said steam supply pipe,

means for removing water of condensation from one of said rolls including a vertically disposed pipe, steam traps in said last-mentioned pipe, means for operating the valve for the steam supply pipe by fluid pressure, a pilot valve for controlling the flow of fluid pressure to said last-

mentioned means, means for operating the pilot valve by the head of water in the vertical pipe between the steam traps, and manually controlled means for governing the flow of water of condensation in the vertical pipe between the steam traps.

4. In a paper-making machine, a drying section including a plurality of drying rolls, means for supplying steam to the rolls, valve means for regulating the supply of steam to the rolls,

and means for regulating the moisture content in the paper sheet leaving said rolls according to the rate of condensation of the steam supplied to said rolls including a condensate-receiving member, means for governing the rate of flow of the condensate from said member, and means actuated in response to variations in the head of condensate in the condensate-receiving member for varying the setting of the steam controlling valve means.

5. In a paper-making machine, a drying section including a plurality of drying rolls, means including a delivery pipe for supplying steam to the rolls, a valve in said delivery pipe for controlling the amount of steam flowing through

said pipe, a measuring member for receiving water of condensation from at least one of said rolls, means governing the rate of flow of water of condensation from said measuring member, and means for controlling the valve in the steam supply delivery pipe according to the head of water of condensation in said measuring member.

HERVEY G. CRAM.
